UNITED STATES PATENT OFFICE

EDWIN W. FUERST, OF TOLEDO, OHIO, ASSIGNOR TO THE PARKER PEN COMPANY, OF JANEVILLE, WISCONSIN, A CORPORATION OF WISCONSIN

DESIGN FOR A BOTTLE OR SIMILAR CONTAINER

Application filed November 23, 1931. Serial No. 41,811. Term of patent 14 years.

To all whom it may concern:

Be it known that I, EDWIN W. FUERST, a citizen of the United States, residing at Toledo, county of Lucas, State of Ohio, have invented a new, original, and ornamental Design for a Bottle or Similar Container, of which the following is a specification, reference being had to the accompanying drawing forming a part thereof.

Fig. 1 is a side plan view of the container; and

Fig. 2 is a top plan view of the said container.

I claim:

The ornamental design for a bottle or similar container, as shown.

EDWIN W. FUERST.
